UNITED STATES PATENT OFFICE.

ADOLF KLEIN, OF VIENNA, AUSTRIA-HUNGARY, ASSIGNOR TO SOCIÉTÉ DES INVENTIONS JAN SZCZEPANIK & CIE., OF VIENNA, AUSTRIA-HUNGARY, A FIRM.

DRAFT-REGULATING APPARATUS FOR FURNACES.

SPECIFICATION forming part of Letters Patent No. 739,321, dated September 22, 1903.

Application filed June 27, 1901. Serial No. 66,272. (No model.)

To all whom it may concern:

Be it known that I, ADOLF KLEIN, a subject of the Emperor of Austria-Hungary, residing at Vienna, in the Province of Lower Austria, in the Empire of Austria-Hungary, have invented certain new and useful Improvements in Draft-Regulating Apparatus for Furnaces; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

A characteristic feature of my invention lies in the provision of means whereby a draft-damper is maintained in a normal or adjusted position relatively to the draft-flue so long as the furnace-door is closed, whereby said damper is maintained in that position when the furnace-door is opened to prevent strong drafts of air across the incandescent fuel, which would deaden it, whereby the damper is caused to move rapidly to a maximum open position when the furnace-door is again closed and to slowly move back to its normal or adjusted position, and whereby the damper is caused to rapidly move to its normal position should the furnace-door be opened when said damper is not in said normal position.

A further characteristic feature of my invention resides in the provision of a resistance antagonizing the aforesaid movements of the damper to cause the same to move slowly from and back to its normal position.

A further characteristic feature of my invention resides in the provision of means for automatically reducing the resistance antagonizing the movement of the damper to its normal position when the furnace-door is opened, so as to cause said damper to rapidly move to its said normal position should said damper not be in that position when the furnace-door is opened; but that my invention may be fully understood I will describe the same in detail, reference being had to the accompanying drawings, in which—

Figure 1 is an elevation, partly in section,

illustrating an automatic draft-regulator embodying my invention applied to a steam-boiler, the casing for the valve controlled by the opening and closing of the furnace-door and the pipes 9, 13, and 14, connecting said casing with the appliances which control the movements of the damper, being omitted. Fig. 1^a is a sectional elevation, drawn to an enlarged scale, of the draft-regulator shown in Fig. 1, the piston-rod and furnace-door being partly broken away. Figs. 2 and 3 are sectional detail views illustrating the main or distributing valve in its position when the furnace-door is open and closed, respectively. Fig. 4 is an enlarged vertical sectional view of the non-return valve of the cataract and the appliances for unseating said valve. Fig. 5 is a detail view of the devices for adjusting the travel of the damper to more or less close the draft-flue. Figs. 6 and 7 are enlarged fragmentary sectional detail views of the valve mechanism which controls the supply of steam to and its exhaust from the power-cylinder, Fig. 6 showing the parts in their relative position when the power-piston is at the limit of its outstroke, as shown in Fig. 1^a, and Fig. 7 showing said parts in their relative positions when said piston is at the limit of its instroke, and Fig. 8 is a sectional view illustrating a simplified construction of the valve mechanism shown in Figs. 6 and 7.

In Fig. 1 I have shown, as an example, my automatic draft-regulator as arranged in front of a steam-boiler B of the Lancashire type, 11 indicating the furnace or fuel door, F the draft-flue, and 6 its damper, connected by any suitable flexible connection, as a chain, cable, or rope, and hereinafter referred to as a "cable" 46, running over guide-pulleys 46' to a drum 48, Figs. 1^a and 5, mounted to revolve in bearings in the branches of a forked terminal of the piston-rod 3. To one of the journals of drum 48 or to said drum, as shown in said Figs. 1^a and 5, is secured a ratchet-wheel 49, engaged by a laterally-projecting tooth on a pawl 50, pivoted to the aforesaid forked terminal of the piston-rod 3, and the arm 52' of said forked terminal is longer than its other arm and is bent at right angles across

the path of the cable 46 and performs the function of an indicator element—namely, a pointer—in conjunction with a complementary indicator element 51, secured to said cable, one end of which is secured to the drum 48, and the latter can be rotated by means of a crank 47 for the purpose of winding thereon more or less of the cable 46, and thereby determining the extent to which the damper is 5 to move into the draft-flue F, and consequently the maximum cut-off, the pawl 50 preventing the unwinding of the cable under the weight of the damper. I am thus enabled to regulate the draft as circumstances may require and at the same time to observe the movements of the damper and see whether the latter works properly. The furnace-door 11 has an arm 11', Figs. 1^a, 2, and 3, that projects into a longitudinal slot 10" in a radial 10 arm 10' on or secured to a four-way main or distributing cock or valve 10, the casing of which has four ports, to which are respectively secured the pipes 9, 12, 13, and 14, the arrangement being such that when the furnace-door is closed the pipes 9 and 12 and the pipes 13 and 14, respectively, will be placed in communication, (see Fig. 3,) while when said furnace-door is opened the pipes 12 and 14 and the pipes 9 and 13, respectively, will 15 be placed in communication, as shown in Fig. 2, for purposes hereinafter explained, the pipe 12 being in communication with the steam space or collector of the boiler. The piston-rod 3, above referred to, carries two 20 pistons 2 and 4, the former working in a cylinder practically open at its lower end, while piston 4 works in the cylinder 5 of a cataract, whereby the damper 6 during normal operation is caused to move at a comparatively low 25 rate of speed to and from its normal or adjusted position. The cataract comprises a horizontal tubular member 5' of comparatively small cross-sectional area and a vertical tubular member or cylinder 5 of relatively large cross-sectional area, both members arranged 30 in T form and in communication with each other. Said cataract comprises, furthermore, a reservoir 35, closed fluid-tight and encompassing the vertical member or cylinder 5 35 and in communication therewith through a comparatively small port 34, near the foot of the cylinder. To one end of the horizontal member 5' of the cataract is connected a circulating-pipe 36, said pipe extending into 40 reservoir 35, near to its bottom, and at the junction of this pipe 36 with said member 5, is located a regulating-valve of any well-known or preferred type for regulating the 45 flow of fluid to and from said pipe and member 5'. To the last-named member 5' of the cataract is connected a second pipe 37, extending also near to the bottom of reservoir 35, and in the branch leading from said member to said pipe 37 is seated a check-valve 16, 50 having an angular arm 39', projecting vertically therefrom, the upper horizontal mem-

ber of which arm is slotted for the reception of the headed end of the stem 39 of a piston-valve 42, said stem also carrying a piston 38, working in a suitable cylinder 15. The piston 38 is under the influence of a spring 41, acting on its upper face and holding it normally at the limit of its instroke on an annular shoulder in the cylinder which is connected below the piston with the pipe 14, 55 leading from the casing of the main or distributing valve 10, hereinbefore referred to. The piston-valve 42 controls the communication between the piston-cylinder 15 and an exhaust-chamber 43 below said cylinder, to 60 which chamber is connected an exhaust-pipe 45, the communication between the chamber and pipe being effected through a peripheral circular port or passage 44, formed near the inner or lower end of valve 42. 65

The described construction is clearly shown in Fig. 4 and the arrangement is such that when the piston 38 is in its normal position the gravity-valve 16 will have sufficient play to move off its seat under pressure of the 70 fluid rising in pipe 37, but preventing or checking the flow of fluid back to the reservoir 35 through said pipe. 75

As is well known, loss of liquid in cataracts as heretofore constructed had to be compensated or made up at once if violent shocks were to be avoided in a cylinder completely filled with liquid during the movement of the damper to its normal position. This disadvantage is obviated in the described construction of cataract, because the instroke of the piston 4 is made at such a slow rate of speed that the cylinder above the piston will at all times be filled with liquid forced thereinto during the instroke. Furthermore, the reservoir 35 need not contain a larger quantity of liquid than is necessary to properly cover or 80 lute the lower open ends of the pipes 36 and 37. In view of this and by using a fluid-tight reservoir I am enabled to use water instead of oil or glycerin, as is necessary in cataracts of usual construction. This use of water has the further advantage in that its 85 resistance is invariable, which is not the case with oil or glycerin, the resistance of which varies with the degree of their viscosity under 90 temperature variations. 95

It will readily be seen that when steam is admitted to the piston-cylinder 15 through pipe 14 the piston 38, and with it the piston-valve 42, will make its outstroke idly for a certain distance, and will then not only unseat valve 16, but bring the reduced portion 44 of the piston into register with exhaust-pipe 45, thus establishing communication between said pipe and chamber 43 to allow water of condensation collecting in said chamber to drain therefrom. By these means I am enabled to keep the piston-cylinder 15 and the steam-supply pipe 14 free from water of condensation, and inasmuch as steam is admitted to cylinder 15 whenever the furnace-door 100

11 is opened, as hereinafter more particularly described, no great amount of water or condensation can collect in the piston-cylinder 15.

Referring now particularly to Figs. 1^a, 6, 5 and 7, at its upper end the power-cylinder 1 is connected through a pipe 7 to an upper chamber 8', formed in a valve-casing 8, having at its lower end a second chamber 8" and below chamber 8' a steam-chamber 81 in communication with said chamber 8' through a valve-port 25, having a seat for a cut-off valve 22, said steam-chamber 81 being in communication with chamber 8" at the lower end of the valve-casing through an axial cylindrical passage 29. In the valve-casing 8 are, furthermore, formed two passages, one, 26, placing steam-chamber 81 in communication with the lower end of the axial passage 29 and chamber 8" and a passage 28 placing the upper chamber 8' in communication with the aforesaid axial passage 29 at a point a little below the steam-chamber 81, the said axial passage communicating at that point with an exhaust-pipe 27. In axial passage 29 works a piston-valve 17, having a reduced portion or throat 17' and a recess or socket in its upper face, in which is seated a coiled spring 23, acting on the aforesaid valve 22 to hold it to its seat and close port 25, the valve 22 being loosely mounted on the rod 18 of piston-valve 17, which rod carries an abutment 24, adapted on its stroke to impinge on valve 22 and unseat the same against the stress of its spring 23. In the lower head of the valve-casing is formed a drain-passage 30, leading from chamber 8", the inlet of which is normally closed by a spring-seated valve 32, pivoted in said chamber and provided with an arm 31, extending into the aforementioned axial passage 29 of the valve-casing, said arm being acted on by the piston-valve 17 on its down or in stroke to unseat valve 32, Fig. 6. The object of this arrangement is to exhaust water of condensation from steam-chamber 8" and the steam-supply pipe, which is connected to steam-chamber 81 of valve-casing 8 and the main or controlling valve 10, hereinbefore referred to, whenever the piston-valve 17 reaches or is about to reach the limit of its stroke. The piston-rod 18 projects through a stuffing-box out of the upper end of valve-casing 8 and is pivoted to the shorter arm of a lever 19, fulcrumed to a standard on the valve-casing, said lever under the stress of a spring 21 acting to draw said shorter arm downwardly, and consequently raise the longer arm, which terminates in a fork 19', Figs. 1^a and 6, embracing the power-piston rod 3, which at a suitable point carries an abutment in the form of a collar 20, which on the stroke of the power-piston 2 impinges upon said fork and tilts lever 19 against the stress of the spring 21, the valve-rod 18 making its out-stroke. During a portion of this stroke the valve 22 will be acted on by its spring 23 to hold it in contact with the abutment 24 on valve-rod 18, which abutment moves out of

contact with said valve before the power-piston has completed its stroke, the valve cutting off the steam from pipe 9 to valve-casing chamber 8', and when said power-piston 2 is about to complete its stroke the piston-valve 17 will be in the position shown in Fig. 7 and bearing on valve 22. In this position of valve 17 its reduced portion 75 will be in register with exhaust-pipe 27 to exhaust the steam from chamber 8' and cylinder 1, allowing the power-piston 2 to make its out-stroke under the weight of the damper. At the same time the lower end of the piston-valve 17 uncovers the outlet-passage 26, admitting live steam to axial passage 29 below said piston-valve and to chamber 8", whereby valve 22 is firmly held to its seat and the piston-valve in its described position, and as 80 valve 17 moves out of contact with arm 31 of drain-valve 32 the latter, under the action of its spring, will close the drain 30.

In Fig. 8 I have shown a preferred form of auxiliary valve mechanism very much simpler than that shown in Figs. 6 and 7. The valve-casing 8 is cylindrical and enlarged at its lower end for the collection of water of condensation and is divided into three chambers c' c² c³ by two piston-valves 17^a and 17^b, 95 secured to the piston-rod 18^a, said cylinder being connected at suitable points intermediate of the pistons to the steam-supply pipe 9 and to the power-cylinder 1 through pipe 7.

In the position of the piston-valve shown in Fig. 8 steam is admitted to power-cylinder 1, its piston 2 making its stroke, the lower piston-valve 17^b acting on the valve-arm 31 to hold the drain-valve 32 off its seat and also cutting off the communication between the chamber c³ and pipe 9 through passage 26^a.

When the abutment 20 on power-piston rod 3 comes into contact with lever 19, the latter is tilted against the stress of spring 21, the valve-rod 18^a and piston-valve making their out-stroke, and when power-piston 2 is about to reach or has reached the limit of its stroke the valves will be at the limit of their out-stroke, valve 17^b uncovering the outlet of passage 26^a and covering the outlet of pipe 9, 115 thus cutting off steam from power-cylinder and admitting steam to the under face of piston-valve 17^b. At the same time piston-valve 17^a will uncover exhaust-passage 27^a, thereby exhausting the steam from power-cylinder 1, the piston of which then makes its out-stroke under the weight of the damper, while the valves will be held in their described positions by the steam-pressure on the under face of valve 17^b until the furnace-door is opened and again closed.

The operation of the appliances described is as follows: The damper 6 having been adjusted to a normal position in the flue controlled thereby by means of the appliances described in reference to Figs. 1^a and 5, the fire is started and the damper held fully open through the medium of the cable 46, and when properly started the damper is released

and the furnace-door closed, the valves 17 and 22 being then in their relative positions (shown in Figs. 1^a and 6) under the action of the spring 21 on valve-lever 19. When the 5 pressure of the steam generated is sufficient to operate the draft-regulating appliances, a valve (not shown) in the steam-main 12 is opened. As hereinabove stated, the normal position of the controlling-valve—namely, its 10 position when the furnace door is closed—is that shown in Fig. 3, from which position it is moved to that shown in Fig. 2, when the furnace-door is opened, while the normal position of the valves 17 and 24 is that shown 15 in Fig. 7, or, in other words, the normal positions of the damper and the aforesaid valves are determined by the limit of the out-stroke of the power-piston 2 and valve-rod 18, as will hereinafter appear. Hence, when 20 the valve in the steam-main is opened and remains open after the pressure of the steam generated in the boiler is sufficient to operate the damper-actuating appliances, steam will flow from pipe 12 to pipe 9 through the 25 passage in the distributing-valve 10, which places these pipes in communication with each other, and from pipe 9 the steam will flow through valve-port 25, valve-casing chamber 8', and pipe 7 to upper end of power-cylinder 30 1, causing its piston 2 to make its instroke. As soon as abutment 20 contacts with the longer arm of valve-lever 19 said lever will be gradually rotated on its pivot against the stress of its spring 21, causing the valves 17 35 and 24 to make their outstroke, the completion of which takes place when the power-piston is about to reach or has reached the limit of its instroke, the position of the valves 17 and 22 being that shown in Fig. 40 7, the supply of steam to the power-cylinder being cut off and said cylinder placed in communication with the exhaust-pipe 27, through pipe 7, casing-chamber 8', passage 28, and reduced portion 17' of piston-valve 45 17, which latter valve has also moved out of contact with the arm on the drain-valve 32, which has closed the drainage-port, while said piston-valve has also uncovered the passage 26 in communication with the receiving- 50 52 chamber 81 in the valve-casing, and consequently with pipe 9, thus admitting steam to the under side of piston-valve 17 to hold it and valve 24 in their said position shown in Fig. 7. As soon as the power-piston 2 is relieved from pressure said piston makes its 55 outstroke under the weight of the damper until the piston has reached the limit of its said outstroke, when the damper 6 will also have reached its normal position in the flue, the 60 various elements remaining in the described positions so long as the furnace-door is closed. Owing to the resistance of the liquid in the cataract to the movements of the piston 4, it will readily be seen that the instroke, as well 65 as the outstroke, of piston 2 is effected very slowly, so that the damper 6 will move to its normal position at a correspondingly slow

rate of speed. The object of this is to provide greater draft for a certain period of time after stoking, and as the instroke of the power-piston is also antagonized by the liquid in the cataract neither stroke can take place suddenly, as would be the case if the movements of the power-piston were not antagonized. The means for producing these slow 70 strokes of the piston 2—namely, the cataract—has been fully described hereinbefore. If now the furnace-door is opened for the purpose of stoking, the distributing-valve 10 being moved to the position Fig. 2, the supply 75 of steam to pipe 9 will be cut off and said pipe placed in communication with exhaust-pipe 13, connected to exhaust-pipe 27, while pipe 14 will be placed in communication with steam-main 12, steam from pipe 9 and from 80 the lower part of valve-casing 8 will be exhausted, valve 17 will be relieved from pressure, and spring 21, acting on valve-lever 19, will move the valves 17 and 22 into their positions shown in Fig. 6. At the same time 85 live steam is supplied to valve-casing 15 and the check-valve 16 is unseated. These operations have no influence on the power-piston, hence do not influence the damper, which 90 remains in its normal position until the furnace door is closed, whereby the controlling-valve 10 will be moved back to its normal 95 position, Fig. 3, and steam admitted to power-cylinder to first move the damper to its full flue-opening position, the valves 17 and 22 100 being moved back to their normal positions, (shown in Fig. 7,) after which said power-piston and damper move back to their normal positions, as above set forth. Should the furnace-door be opened while the power-piston 105 2 is making its outstroke, the check-valve 16 will be unseated, as above described, thus opening an additional outflow-channel for the cataract liquid above the piston 4 and one of greater area, thereby reducing the 110 resistance on piston 4 to such an extent as to enable the power-piston under the weight of the damper to make its outstroke very rapidly, the damper 6 moving rapidly to its normal position, as will be readily understood 115 and for the purposes hereinbefore described.

From the above description the operation of the valves shown in Fig. 8 will be fully understood.

Having thus described my invention, what I claim as new therein, and desire to secure by Letters Patent, is—

1. The combination with the fuel-door of a furnace, its damper, a power-cylinder, its piston connected to said damper and a resistance 125 antagonizing the movements of said piston; of means controlled by the movements of the fuel-door, operating to admit motive fluid to the power-cylinder to drive its piston in one direction, then to cut off and exhaust motive 130 fluid from said cylinder to allow the piston to make its return stroke under the weight of the damper when the fuel-door is closed and to reduce the resistance to the return stroke

of the piston when the fuel-door is opened during said return stroke, for the purpose set forth.

2. The combination with the fuel-door of a furnace, its damper, a power-cylinder, its piston connected to said damper, a resistance antagonizing the movements of the piston in either direction and means for regulating said resistance; of means controlled by the movements of the fuel-door, operating to admit motive fluid to the power-cylinder to drive its piston in one direction, then to cut off and exhaust motive fluid from said cylinder to allow the piston to make its return stroke under the weight of the damper when the fuel-door is closed and to reduce the resistance to the return stroke of the piston when the fuel-door is opened during said return stroke, for the purpose set forth.

3. The combination with the fuel-door of a furnace, its damper, a power-cylinder, its piston connected to said damper, a cataract comprising a cylinder, a piston connected to the power-piston, means placing opposite ends of said cataract-cylinder in communication, an auxiliary passage also placing said opposite ends in communication, and a valve in said auxiliary passage, closing said auxiliary passage; of means controlled by the movements of the fuel-door, operating to admit motive fluid to the power-cylinder to drive its piston in one direction, then to cut off and exhaust motive fluid from said cylinder to allow the piston to make its return stroke under the weight of the damper when the fuel-door is closed, and to open the valve in the aforesaid auxiliary passage of the cataract, when the fuel-door is opened, for the purpose set forth.

4. The combination with the fuel-door of a furnace, its damper, a power-cylinder, its piston connected to said damper, a cataract comprising a cylinder, a piston connected to the power-piston, means placing opposite ends of said cataract-cylinder in communication, an auxiliary passage also placing said opposite ends in communication, and a gravity-valve in said auxiliary passage, closing said auxiliary passage; of means controlled by the movements of the fuel-door, operating to admit motive fluid to the power-cylinder to drive its piston in one direction, then to cut off and exhaust motive fluid from said cylinder to allow the piston to make its return stroke under the weight of the damper when the fuel-door is closed, and to unseat the valve in the aforesaid auxiliary passage of the cataract; when the fuel-door is opened, for the purpose set forth.

5. The combination with the fuel-door of a furnace, its damper, a power-cylinder, its piston connected to said damper, a cataract comprising a cylinder, a piston connected to the power-piston, means placing opposite ends of said cylinder in communication, an auxiliary passage, also placing said ends in communication, and a valve in said passage arranged to move off its seat under the pressure of as-

cending liquid and to move to its seat under the pressure of descending liquid; of means controlled by the movements of the fuel-door, operating to admit motive fluid to the power-cylinder to drive its piston in one direction, then to cut off and exhaust motive fluid from said cylinder to allow its piston to make its return stroke under the weight of the damper when the fuel-door is closed, and to unseat the valve in the auxiliary passage of the cataract when the fuel-door is opened, for the purpose set forth.

6. The combination with the fuel-door of a furnace, its damper, a power-cylinder, its piston connected to said damper, a cataract, comprising a cylinder, a piston connected to the power-piston, means placing opposite ends of said cataract-cylinder in communication, an auxiliary passage also placing said opposite ends in communication, a check-valve closing said passage, a piston-cylinder, a piston and its rod connected to said valve; of means controlled by the movements of the fuel-door, operating to admit motive fluid to the power-cylinder to drive its piston in one direction, then to cut off and exhaust motive fluid from said power-cylinder and from the check-valve piston-cylinder, when the fuel-door is closed, and to admit motive fluid to the last-mentioned cylinder to cause its piston to unseat the aforesaid check-valve when the fuel-door is opened, for the purpose set forth.

7. The combination with the power-piston, a damper connected thereto, a cataract comprising a receiver, a cylinder therein, a piston working in said cylinder and connected to the power-piston, said cataract-cylinder open at its upper end and having a port at its lower end, a passage across the upper end of said cylinder, return-pipes extending from opposite ends of said passage near to the bottom of the receiver, a gravity check-valve in one of said pipes, a cylinder, its piston and piston-rod connected to said valve to allow it to move off its seat independently of the piston under the pressure of ascending liquid; of means, controlled by the movements of the fuel-door of a furnace, operating to admit motive fluid to the power-cylinder to drive its piston in one direction, then to cut off and exhaust motive fluid from said power-cylinder to allow its piston to make its return stroke under the weight of the damper, and to exhaust motive fluid from the check-valve piston-cylinder when the fuel-door is closed, and to admit motive fluid to said check-valve cylinder to cause its piston to unseat the check-valve when the fuel-door is opened, for the purposes set forth.

8. The combination with the power-piston, a damper connected thereto, a cataract comprising a receiver, a cylinder therein, a piston working in said cylinder and connected to the power-piston, said cataract-cylinder open at its upper end and having a port at its lower end, a passage across the upper end of said cylinder, return-pipes extending from oppo-

site ends of said passage near to the bottom of the receiver, a regulating-valve in one of said pipes, a gravity check-valve in the other pipe, a cylinder, its piston and piston-rod 5 connected to said valve to allow it to move off its seat independently of the piston under the pressure of ascending liquid; of means, controlled by the movements of the fuel-door of a furnace, operating to admit motive fluid 10 to the power-cylinder to drive its piston in one direction, then to cut off and exhaust motive fluid from said power-cylinder to allow its piston to make its return stroke under the weight of the damper, and to exhaust motive 15 fluid from the check-valve piston-cylinder when the fuel-door is closed, and to admit motive fluid to said check-valve cylinder to cause its piston to unseat the check-valve when the fuel-door is opened, for the purposes 20 set forth.

9. The combination with the fuel-door of a furnace, the damper, a power-cylinder, its piston and piston-rod connected to said damper, a valve-casing having admission, delivery and exhaust ports, a valve-chamber, and a passage leading from said admission-port to the inner end of said chamber, a pipe connecting the delivery-port of the casing with the outer end of the power-cylinder, a valve in 25 said chamber controlling said ports and passage, means automatically unseating the valve to admit motive fluid to the power-cylinder and close the exhaust-port and the inner end of said passage, and means operated 30 by the piston-rod on the instroke of the piston to seat the valve and open the exhaust and inner end of the aforesaid passage; of a pipe connecting the admission-port of the valve-casing to a source of supply of motive fluid, 35 and a distributing-valve in said pipe operated by the movements of the fuel-door and operating to exhaust motive fluid from the pipe when the fuel-door is opened and to admit motive fluid to said pipe when again closed, 40 for the purpose set forth.

10. The combination with the fuel-door of a furnace, the damper, a power-cylinder, its piston and piston-rod connected to said damper, a valve-casing having admission, delivery and exhaust ports, a valve-chamber, a passage leading from the inner end of said chamber to the admission-port, a drainage-port in the lower head, and a pivotally-arranged spring-seated valve closing said port, 45 said valve having an arm projecting into the lower end of the valve-chamber, a pipe connecting the delivery-port with the outer end of the power-cylinder, a controlling-valve organized to control the admission and exhaust 50 of motive fluid to and from the power-cylinder also controlling the outlet of the aforesaid passage and the drain-valve, means for automatically unseating the valve and thereby establishing communication between the 55 admission and delivery ports, closing the exhaust-port and the outlet of the aforesaid passage, and at the same time unseating

the drain-valve, and means operated by the piston-rod on the instroke of the power-piston to seat the valve and thereby cut off the delivery-port from the admission-port, and simultaneously therewith open the exhaust-port and the outlet of the aforesaid passage and close the drain-valve; of a pipe connecting the admission-port to a source of supply 75 of motive fluid, a distributing-valve in said pipe operated by the movements of the fuel-door and operating to admit motive fluid to the aforesaid pipe when the fuel-door is opened, and to cut off and exhaust motive fluid from 80 the pipe when again closed, for the purpose set forth.

11. The combination with the fuel-door, the power-cylinder, its piston and rod to which the damper is connected, said rod carrying an 85 abutment, a valve-casing having admission, delivery and exhaust ports, said delivery-port connected to the outer end of the power-cylinder, a pipe connecting the admission-port to a source of supply of motive fluid, a drain- 90 port in the lower head of the casing, a spring-seated, pivotally-mounted valve for said port provided with an arm, and a passage in the valve-casing leading from its inner end to the admission-port; of a twin piston-valve, its 95 rod, a lever pivoted intermediate its ends to said rod, one end of said lever projecting into the path of the abutment on the power-piston rod, a spring acting on the other end of the lever to cause the valve to make its instroke, thereby placing the admission and delivery ports into communication, cutting off the exhaust-port and inner end of aforesaid passage and unseating the drain-valve, and a distributing-valve in the aforesaid supply- 105 pipe operated by the movements of the fuel-door to admit motive fluid to the pipe when the fuel-door is closed and to cut off and exhaust motive fluid from said pipe when said door is opened, for the purpose set forth. 110

12. The combination with the damper of a furnace, a power-cylinder and piston, the piston-rod bifurcated at its outer end, one of the arms of the fork longer than the other and provided with a horizontal index-finger, a 115 revoluble drum mounted in the fork, and a locking device to lock said drum against rotation; of a cable having one end secured to the drum and the other to the damper, said cable carrying a complementary indicating 120 device proximate to the aforesaid index-finger, for the purpose set forth.

13. The combination with the power-cylinder, its piston and piston-rod and means for reciprocating said piston; of a cataract comprising a fluid-tight receiver 35, a cylinder 5 having a small port 34 at its inner end and a tubular outer cross-head, return-pipes at each end of said cross-head and extending near to the bottom of the receiver, and a piston working in said cylinder and carried by the power-piston rod; of a regulating-valve in one of said return-pipes, a gravity check-valve 16 in the other return-pipe, an auxiliary piston-

cylinder, a collector for water of condensation in communication with said cylinder, said collector provided with a drain-port, a piston 38 working in said cylinder, a spring 5 acting on the outer face of the piston, the piston-rod 39 loosely connected to a projection on the valve 16, a piston-valve 42 on said rod controlling the communication between the cylinder and collector, and means for periodically admitting motive fluid to the inner face of piston 38 to unseat the check-valve and

thereby cause the piston-valve 42 to uncover the drain-port of the collector and then to exhaust the motive fluid, for the purpose set forth.

In testimony that I claim the foregoing as my invention I have signed my name in presence of two subscribing witnesses.

ADOLF KLEIN.
